US00D906666S

(12) **United States Design Patent** (10) Patent No.: **US D906,666 S**
Gannet et al. (45) Date of Patent: ** Jan. 5, 2021

(54) **FLEXIBLE CONTAINER WITH HANDLES**

(71) Applicants: **Leonard Gannet**, Morristown, NJ (US); **Simon Shevelev**, Wyckoff, NJ (US)

(72) Inventors: **Leonard Gannet**, Morristown, NJ (US); **Simon Shevelev**, Wyckoff, NJ (US)

(**) Term: **15 Years**

(21) Appl. No.: **29/683,469**

(22) Filed: **Mar. 13, 2019**

(51) LOC (13) Cl. **03-01**

(52) U.S. Cl.

USPC **D3/232**

(58) **Field of Classification Search**

USPC D3/232-233, 240-243, 245-246
CPC A45C 1/024; A45C 3/06

(57) **CLAIM**

The ornamental design for a flexible container with handles, as shown and described.

DESCRIPTION

FIG. 1 is a top, front side and left end perspective view of a flexible container with handles;
FIG. 2 is a left end view of the container;
FIG. 3 is a right end view of the container;
FIG. 4 is a top view of the container;
FIG. 5 is a bottom view of the container;
FIG. 6 is a front side view of the container;
FIG. 7 is a rear side view of the container; and,
FIG. 8 is a top, front side and left end perspective view of the container, with a bundle of firewood loaded and retained therein.

The broken lines in the drawings form no part of the claimed design.

1 Claim, 8 Drawing Sheets
